UNITED STATES PATENT OFFICE.

ELFREDA BEGY, OF ROCHESTER, NEW YORK.

GARMENT HANGER.

Application filed April 19, 1926. Serial No. 102,968.

My present invention pertains to garment hangers, and contemplates the provision of a garment hanger designed more especially for holding and hanging fine dresses, and this in such a manner that there is no liability of the dress slipping from the hanger, nor is there any liability of the dress changing its position relative to the hanger with the result that the dress is maintained in good condition so long as it is engaged with the hanger.

To the attainment of the foregoing, the invention consists in the improvement as hereinafter described and definitely claimed.

In the accompanying drawings, forming part of this specification:—

Figure 1 is a top plan view of the garment hanger constituting the best practical embodiment of my invention of which I am cognizant, the shank of the suspending hook being shown in section.

Figure 2 is a side elevation of the hanger.

Figure 3 is an enlarged fragmentary section illustrative of the central portion of the hanger.

Similar numerals of reference designate corresponding parts in all of the views of the drawings.

Among other elements my novel hanger comprises a curvilinear body bar 1, preferably, though not necessarily, of wood. At opposite sides of its transverse median line the body bar 1 is provided with apertures 2, Figures 1 and 3, and extending through the center of the said body bar 1 is the shank 3 of a suspending hook 4, the said shank 3 being enlarged at its lower end as designated by 5 so that the body bar 1 is adequately supported on the said shank.

The said apertures 2 in the body bar 1 contain pins 6, Figures 2 and 3, and the said pins 6 are designed to serve for the connection in pivotal manner of the clamping arms 7 of the improvement. Each of the said clamping arms 7 is preferably formed of appropriate wire and is curved as shown and is equipped at its outer end with an appropriate pad 8, the said pad 8 being designed to enable the arm to securely clamp a dress on the body bar 1 and this without liability of the dress being discolored or injured or distorted. Each of the said clamp arms 7 is provided at its inner end with a pendent loop-shaped portion 9 which is disposed in one aperture 2 and straddles

one pin 6, and the said loop 9 is merged into an upstanding loop 10 which constitutes a convenient handle for moving the pad end of the clamp arm away from the body bar 1, and the said upstanding loop 10, in turn, is merged into a downwardly extending terminal portion 11, disposed and movable in the aperture 2. The lower ends of the terminal portions 11 are disposed below the body bar 1 and are connected through the medium of a retractile spring 12, the ends 13 of the said spring being appropriately connected to the ends of the pendent portions 11, and the said spring having for its function to yieldingly maintain the pad ends 8 of the arms 7 against the upper side of the body 1 so that the said arms 7 will serve efficiently in positively holding a dress on the body bar 1 and against casual movement on or displacement from the said body bar 1.

The upstanding loops 10 are arranged sufficiently close together to enable an operative with one hand to take hold of said portions 10 and by moving the same toward each other raise the pad ends of the arms 7 from the body bar 1, and when this is done a dress may be manifestly positioned on the body bar 1 quickly and easily, and when the upstanding portions 10 are released, the pad ends of the arms 7 will obviously clamp the dress on the body bar 1 so that the dress will be secured on the hanger in neat fashion and without liability of the dress shifting on the hanger and also without liability of the dress being casually released from the hanger.

Notwithstanding the capacity of function ascribed to my improved garment hanger, it will be appreciated that the hanger is simple and inexpensive in construction and is quite as durable as ordinary hangers such as at present are in general use. It will also be appreciated that my novel hanger is susceptible of ready adjustment for the placing of a dress on the hanger and also for the removal of a dress from the hanger and this without liability of injury to the dress.

I have specifically described the preferred embodiment of my invention which has been successfully used in actual practice. I do not desire, however, to be understood as limiting myself to the precise construction and relative arrangement of elements as illustrated and described, my invention being

defined by my appended claim within the scope of which modifications may be made without departure from my invention.

Having described my invention, what I claim and desire to secure by Letters Patent, is:—

A garment hanger comprising a curvilinear body bar with spaced apertures at opposite sides of the transverse median line thereof, central means for suspending said body bar, pins carried by the body bar and extending across said apertures, clamping arms arranged above the body bar and hav-

ing at their inner ends pendent loops straddling said pins and also having upstanding loops into which said pendent loops are merged and further having terminal portions depending from the upstanding loops and extending through the apertures in the body bar to points below said bar, and a longitudinally disposed retractile spring disposed below the body bar and interposed between and connected to the said terminal portions. 15 20

In testimony whereof I affix my signature.

ELFREDA BEGY.
